ELECTRICAL JUNCTION BOX OR SIMILAR ARTICLE

Philip G. Stone, New York, N. Y.

Application September 26, 1947, Serial No. 141,591

Term of patent 7 years

(Cl. D26—1)

To all whom it may concern:

Be it known that I, Philip G. Stone, a citizen of the United States, residing at New York city, in the county of Kings and State of New York, have invented a new, original, and ornamental Design for an Electrical Junction Box or Similar Article, of which the following is a specification, reference being had to the accompanying drawing, forming part thereof.

In the drawing

Fig. 1 is a front elevational view of an electrical junction box, showing my new design;

Fig. 2 is a side elevational view thereof;

Fig. 3 is a top plan view;

Fig. 4 is a bottom plan view; and

Fig. 5 is a cross-sectional view taken on the line 5—5 of Fig. 2.

I claim:

The ornamental design for an electrical junction box or similar article, as shown.

PHILIP G. STONE.
